[57] CLAIM

The ornamental design for a box for cosmetic products or the like, substantially as shown and described.

DESCRIPTION

FIG. 1 is a front right perspective view of a box for cosmetic products or the like showing my new design in open condition;

FIG. 2 is a front right perspective view in closed condition thereof;

FIG. 3 is a top plan view thereof;

FIG. 4 is a front side elevational view thereof;

FIG. 5 is a bottom plan view thereof;

FIG. 6 is a left side elevational view thereof, the right side view being a mirror image of the left view.

FIG. 1

FIG. 2

FIG. 3

FIG. 4

FIG. 5

FIG. 6
